UNITED STATES PATENT OFFICE.

HENRY H. SCHLEBER, OF ROCHESTER, NEW YORK.

CIGARETTE.

SPECIFICATION forming part of Letters Patent No. 258,255, dated May 23, 1882.

Application filed August 24, 1881. (No model.)

To all whom it may concern:

Be it known that I, HENRY H. SCHLEBER, of Rochester, Monroe county, New York, have invented an Improvement in Cigarettes, of 5 which the following is a specification, reference being had to the annexed drawings.

The object of my invention is to provide cigarettes with a mouth-piece which will be exceedingly cheap, and which at the same time 10 shall be adapted to absorb the nicotine and other poisonous matters set free by the burning of the tobacco, and which shall retain, when moist, the proper degree of rigidity to maintain the body of the cigarette in position.

15 To this end my invention consists in a mouth-piece composed of a long strip of light porous wood wound in such manner as to form a cylinder with the grain lying in line with its axis. The mouth-piece thus constructed will absorb 20 readily the nicotine and oils set free from the tobacco and prevent them from passing to the mouth of the smoker. At the same time the cylinder, owing to the fact that the grain of the wood runs lengthwise thereof, will retain, 25 when moist, a sufficient degree of rigidity to sustain properly the body of the cigarette, the shaving being wound upon itself in such manner as to produce a cylinder of a length equal to the width of the shaving. The mouth-piece 30 possesses a considerable degree of solidity, and consequently is in no danger of being closed by the pressure of the teeth in such manner as to prevent the passage of the smoke through it.

35 I am aware that mouth-pieces have been made of glass, of paper coiled in the form of a cylinder, of broom-straw, and of husks and banana-leaves, the latter being practically non-absorbent.

40 I am also aware that it has been proposed in a patent to form a mouth-piece of a strip of paper, wood, or other similar material by coiling the same in a spiral form, thus producing a light tapering tube of a length many times greater 45 than the width of the strip employed. The patent did not, however, disclose any special advantage resulting from the use of the wood, nor did it state that the grain of the wood was to lie lengthwise of the mouth-piece. Moreover, the mouth-piece constructed in accordance with the patent would possess little stiff-

ness and would become useless when subjected to the pressure of the teeth.

My improved mouth-piece or absorptive filling for the mouth end of cigarettes is represented in the accompanying drawings, in which—

Figure 1 is a side view of the finished cigarette. Fig. 2 is an end view of the absorptive filler. Fig. 3 is an end view of the mouth end 60 of the finished cigarette. Fig. 4 is an end view of the absorptive filler partially unrolled. Fig. 5 is a central longitudinal section through the filler. Fig. 6 is a plan view of the filler unrolled.

In the manufacture of my improvement I 65 make the absorptive filler by planing or otherwise removing from wooden blocks shavings of suitable length and width, having their fibers running at right angles with their length. Suitable dimensions for the shavings are one inch 70 in width and three inches in length and a thickness about equal to that of ordinary card-board; but these dimensions may be changed to suit any particular size or grade of cigarette. I prefer to make the shavings from some soft light-colored wood, such as linden, white-wood, or white birch. A wood free from taste when placed in the mouth should be selected.

The cigarettes are made in the usual way, the mouth end being rolled empty, or the tobacco filling drawn or pushed through, so as to afford space for the introduction of the rolled wooden shaving. The absorptive filling or shaving is rolled on itself into a cylinder, having the fiber of the wood parallel to its axis, and 85 compressed sufficiently to allow its introduction into the unfilled end of the cigarette. The filling is held in place within the paper tube by its expansion after being inserted therein, no gum or other adhesive material being necessary to hold it in place.

90 My improvement will be readily understood from an inspection of the accompanying drawings, in which *a* represents the paper covering of the cigarettes, and *b* the absorptive filler or mouth-piece, consisting of a rolled wooden shaving inserted into the mouth end of the cigarettes.

Cigarettes provided with my improved absorptive filling will be found to possess many 100 advantages over those ordinarily used, the wooden filling being superior to any other ma-

terial hitherto employed for this purpose, since it is cleaner and more fully absorbs the nicotine and moisture than cotton, cork, or corn-husks; and it is cheaper to manufacture, being held 5 in place when inserted within the paper tube by its expansion, without the employment of adhesive material.

Wood possesses a special advantage for use as a mouth-piece, in that when moistened it 10 retains its stiffness or rigidity in the direction of the length of its fiber, so that although the mouth-piece may become thoroughly saturated by the saliva and nicotine it still retains a sufficient degree of rigidity to prevent its bending 15 or doubling down, and thereby permitting the body of the cigarette to fall.

I am aware that mouth-pieces have been made of glass, paper, and other materials. The former are objectionable because they are not 20 absorbent, and the latter objectionable because when thoroughly moistened they become soft

and pliable, losing their strength and doubling or bending in the middle, so as to permit the cigarette to fall.

Having thus described my invention, what 25 I claim is—

1. As a new article of manufacture, the cigarette having its mouth-piece composed of a long strip or ribbon of soft absorbent wood of uniform, or substantially uniform, width, with 30 the grain running transversely, coiled endwise upon itself into a cylindrical form, whereby it is adapted to absorb the nicotine and sustain the cigarette-body when moist.

2. The mouth-piece of a cigarette, consisting 35 of a thin ribbon of absorbent wood wound closely into cylindrical form, the grain of the wood lying lengthwise of the cylinder.

HENRY H. SCHLEBER.
